UNITED STATES PATENT OFFICE.

ROBERT E. PHILLIPS, OF PORTLAND, OREGON, ASSIGNOR OF ONE-FOURTH
TO V. B. ZOLLARS, OF SAME PLACE.

CURTAIN-FIXTURE.

SPECIFICATION forming part of Letters Patent No. 624,860, dated May 9, 1899.

Application filed January 14, 1898. Serial No. 666,707. (No model.)

To all whom it may concern:

Be it known that I, ROBERT E. PHILLIPS, residing at Portland, in the county of Multnomah and State of Oregon, have invented a new and Improved Curtain-Fixture, of which the following is a specification.

This invention relates to improvements in that class of curtain-fixtures in which the supporting-bracket is made adjustable to fit different widths of windows and which has means for attaching it to the cornice or window-frame without the aid of screws or nails.

The invention has for its object to provide a curtain-fixture of this character, of a very simple and economical construction, which can be readily fitted to and supported on the top window-frame or cornice-piece, which can be quickly adjusted to the width desired, and which will present a neat and ornamental appearance.

The invention consists in certain novel features of construction and peculiar combinations of parts, such as will be first described in detail and then be specifically pointed out in the appended claims, reference being had to the accompanying drawings, in which—

Figure 1 illustrates the preferred form of my invention. Fig. 2 is a detail perspective view of one end of the supporting-bar and one of the combined hanger and bracket members. Fig. 3 is a detail view of a modified form of bracket and hanger. Fig. 4 is a similar view of a further modification. Figs. 5, 6, and 7 are detail views of further modifications hereinafter referred to.

In the accompanying drawings, in which like numerals indicate like parts in all the figures, 1 indicates a supporting-bar, which in the preferred construction is a single member of a length somewhat less than the ordinary width of windows, and in practice such bar may be formed of wood or a light but stout metal plate.

Upon each end of the bar 1 is adjustably secured a combined bracket and supporting member 2, formed of a single piece of sheet metal having a vertical or hanger portion 2^a, the upper end of which is bent over, as at 2^b, and provided with spurs 2^c, whereby it can

be hung and securely held on the top of the window casing or cornice, as clearly shown in the drawings. The lower end of the hanger portion 2^a is bent at right angles to form a horizontal adjusting member 2^d, which is slotted at 2^e and which has its outer end bent forward at right angles to form a bracket-piece 2^f, in which the curtain-roll spindle is supported, it being understood that when used with the ordinary form of spring-roll one of such brackets 2^f has the usual slotted bearing, while the other has the usual circular aperture.

The combined bracket and supporting members 2 are adjustably held on the bar 1 by set-screws 3, which pass through the slots 2^e and engage the bar, as clearly illustrated in Fig. 2 of the drawings.

So far as described it will be readily seen that to fit the fixture to the window-casing it is only necessary to move the members 2 endwise on the bar to the proper width, secure them to their adjusted position, and hang them from the upper edge of the window casing or cornice.

Instead of adjustably securing the combined support and bracket members 2 on the bar 1, such bar may be made of extensible sections, as shown in Figs. 3 and 4, and the said members fixedly secured to the ends of such bar 1. When this form of bar 1 is used, the member 2, when formed of a single piece, is extended down over the front of bar 1, bent under such bar, as at 2^e, then up over the back, as at 2^a, then outward at right angle upon itself, and then forward at right angle to the last bend 2^b, to form the curtain-roll-supporting bracket-piece 2^f, such bending of the piece 2 providing a pocket into which the end of bar 1 fits, which is held closed over the outer end of such bar, the bar and piece 2 being secured together by a screw or brad 4.

Instead of forming the member 2 of a single piece, such member may be formed of a hanger 20, having the top portion for securing it to the upper edge of the casing, and inwardly-projecting spurs 21 at the lower end to engage the casing and assist in holding the fixture in a secure position. In this latter form a sup-

plemental piece 22 is used, which is riveted to the piece 20, bent over the front of the bar 1, secured thereto by a brad or screw, and bent outward at right angle to form the bracket-pieces 24, as clearly shown in Fig. 4.

In Fig. 5 the hanger is shown formed of a single piece of strap metal, the pendent portion 30 of which is bent at an angle, as at 31, down to form a spring-eye 32, back upon itself to form a pocket to receive the end of bar 1, then diagonally to form a brace 33; then into trough or seat 34 to receive the end of the curtain-pole, and then back to form an attaching member 35, adapted to be made fast to the member 30.

Fig. 6 shows the form of bracket shown in Fig. 5, without the curtain-pole-rest portion.

When the form of bracket shown in Figs. 5 and 6 is used, the bar 1 is made non-adjustable, and the spindles 50 50^a of the curtain-roller 40 are made adjustable by having one or both fixed to the curtain-shaft by screw connections, as indicated in Fig. 8.

From the foregoing description, taken in connection with the drawings, it is thought the advantages of my improvement will readily appear. It will be seen that the same can be securely attached to a window-frame without the aid of screws or nails and can be almost instantly adjusted to suit the width of the window.

Having thus described my invention, what

I claim, and desire to secure by Letters Patent, is—

1. A curtain-fixture, consisting of a single sheet-metal member formed into an upper straight or hanger portion having at the upper end an angle member adapted to seat on and grip the top of the window-casing, the lower end of said hanger portion terminating in a horizontal supporting member adapted to receive a brace or supporting-bar, said supporting-member being bent at an angle to the straight portion and projected forward and forming a bracket, substantially as shown and described.

2. A curtain-fixture, consisting of a single sheet-metal member formed into a straight or hanger portion 2, having an angle-spur equipped upper end, said portion 2, having its lower end terminating in a horizontal supporting member said member having its end extended at right angles to form a bracket and having in its supporting portion a longitudinal slot; the cross-bar 1 and the headed screw or ball 3 secured to the cross-bar and slidable in the slot of the supporting portion 2 of the fixture, all being arranged substantially as shown and described.

ROBT. E. PHILLIPS.
